UNITED STATES PATENT OFFICE.

FRED ELLSWORTH MARTIN, OF OAKVILLE, ONTARIO, CANADA, ASSIGNOR TO CHARLES ARMEL BOONE AND SAMUEL WEYLIE McKEOWN, OF TORONTO, CANADA.

BOAT LAUNCHING AND STOWING APPARATUS.

No. 806,146.

Specification of Letters Patent.

Patented Dec. 8, 1908.

Application filed February 27, 1906. Serial No. 418,681.

To all whom it may concern:

Be it known that I, FRED ELLSWORTH MARTIN, of the town of Oakville, in the county of Halton and Province of Ontario, Dominion of Canada, have invented certain new and useful Improvements in Boat Launching and Stowing Apparatus; and I hereby declare that the following is a full, clear, and exact description of the same.

10 This invention relates to a device by which a boat can be quickly and easily lowered from a ship's deck into the water, and as quickly and easily raised from the water and stowed in a fixed place on the ship's deck, and 15 it relates particularly to the specific construction and arrangement of the parts which provide for the launching and stowing of the boat as hereinafter described and particularly pointed out in the claims.

20 For an understanding of the invention reference is to be had to the following description and to the accompanying drawings in which:

Figure 1, is a plan view of the apparatus looking at it from the top. Fig. 2, is a rear elevation of the parts shown in Fig. 1. Fig. 3, is an end elevation with part of the trackways removed showing the davit cranes, davit falls, winding gear for the davit falls, 30 friction brakes for the winding gear and the boat saddles. Fig. 4, is an elevation of the parts shown in Fig. 3, looking at them from the opposite side. Fig. 5, is a perspective view of one of the davit cranes. Fig. 6, is a 35 perspective view of the boat saddles and boat hooks. Fig. 7, is a perspective view of the davit carriage operating gear. Fig. 8, is a detail view of part of the winding mechanism for the davit falls with the view partly in section. Figs. 9 and 10, are detail views of the 40 friction brake for the winding mechanism.

Like characters of reference refer to like parts throughout the specification and drawings.

45 Securely fastened to the deck 1 are two parallel trackways 2 leading to the ship's sides and laterally separated from one another by at least the length of the boat to be held by the davit cranes. Each trackway is 50 formed by two channel beams 2^a, with their bottom flanges 2^b constituting the treads for the davit carriages and securely fastened to the deck, and their top flanges 2^c separated from one another by an unoccupied space to 55 permit of the movement of the davit car-

riages on the treads. Traveling upon the tread of each trackway is a davit carriage 3 consisting of an I-beam 3^a extending lengthwise of the trackway, a truck 4, secured to the bottom flanges 3^b of the I-beam, and anti-friction rollers 5 journaled to the truck 4 and arranged to travel on the tread of the trackway. Journaled to each I-beam 3^a are anti-friction rollers 6 to contact the inner surfaces of the top flanges 3^b, and assist the anti-friction rollers 5 in maintaining the davit carriage in an upright position.

Secured to each davit carriage 3 is a davit crane 7 consisting of an arc shaped I-beam extending from the inboard end of the davit carriage, in an upwardly and outboard curved direction, and secured to each davit crane near the upper end thereof is a brace 8 the lower end of which is secured to the outboard end of the davit carriage so that the stress of the crane and the load thereon will be evenly distributed between the inboard and outboard ends of the davit carriage. Projecting from the upper ends of the inner faces of the davit cranes are studs 9, and 75 revolvably mounted on the studs 9 are grooved idlers 10. Projecting horizontally from the inner faces of the davit cranes 7, immediately above the davit carriages 3, are horizontal plates 11 to which is rigidly bolted a channel beam 12 to couple the davit carriages together and cause their united movement as they travel on the trackways. Bolted to the under side of the channel beam 12 is a channel beam 13 to increase the rigidity of the channel beam 12, and connected to the channel beam 13 and to the davit cranes 7 are stayrods 14. Projecting centrally from the top of the channel beam 12 is a shaft bearing 15, and secured to the davit cranes 7 are journal boxes 16 the bearings of which are aligned with the shaft bearing 15 and journaled in the shaft bearing 15 and journal boxes 16 is a winding shaft 17. One end of the winding shaft 17 projects beyond the outer side of the adjacent davit crane 7, and mounted on the projecting end of the winding shaft 17 is a spur wheel 18 meshing with a pinion 19 journaled to the adjacent davit crane 7. The pinion 19 is rotated, by a 100 crank 20, to revolve the spur wheel 18 and winding shaft 17. Connected to the spur wheel 18 is a friction drum 21 and embracing the friction drum 21, is a brake strap 22, one end of which is permanently connected to a 105 110

plate 23 forming part of or attached to the davit crane 7, and the other end of which is provided with a bolt 24, which extends through an aperture in the plate 23 and is fitted with a hand wheel or nut 25 by which the frictional contact of the brake strap 22 with the friction drum 21 can be increased or diminished.

Mounted on the winding shaft 17 are winding drums 26 alined with the grooved idlers 10 and connected to the winding drums 26 are davit falls 27. The davit falls 27 extend from the winding drums 26 over the grooved idlers 10, and are provided with boat hooks 28 to engage with the boat rings of the boat (not shown).

Suspended from the under side of the horizontal plates 11 are shaft bearings 29 and suspended from the channel beam 12 is a shaft bearing 30 alined with shaft bearings 29. Journaled in the shaft bearings 29 and 30 is a heaving shaft 31 provided with pinions 32 which mesh with the stationary racks 33 connected to the inner sides of the trackways 2. Mounted on the heaving shaft 31 is a worm wheel 34 and meshing with the worm wheel 34 is a worm 35, journaled in bearings 36, suspended from the channel-beam 12.

The worm 35 is provided with a spur wheel 37 meshing with a spur wheel 38 having an axle 39 journaled in bearings 40, extending from the channel beam 12. The axle 39 is fitted to receive a crank 41 by which the spur wheel 38 is rotated to cause the revolution of the spur wheel 37 and worm 35. The revolution of the worm 35 causes the revolution of the worm wheel 34, heaving shaft 31, and pinions 32.

The boat in its inboard position is supported on boat saddles 42 hinged to the deck so that they can be lowered into contact with it or raised into a plane at an angle thereto. Lashing hooks 43 are fastened to the deck by flexible boat lashings 44 capable of being tightened to draw the lashing hooks tightly against the gunwales of the boat and force the keel and bottom of the boat tightly into contact with and hold it immovable on the boat saddles which are locked in their raised position by hooks 42 connected to the deck 1.

When it is desired to launch the boat, the hooks 42 are disconnected from the boat saddles 42, the boat lashings are slackened and the lashing hooks are disengaged from the boat gunwale. The davit falls are then tightened to relieve the boat saddles of the weight of the boat so that the boat saddles can move to their lowered position. The crank 41 is then turned in the direction indicated by arrow to revolve the spur wheel 38 and cause the revolution of the spur wheel 37, worm 35, worm wheel 34, and heaving shaft 31. The revolution of the heaving shaft 31 causes the pinions 32 to revolve

and engage with the teeth of the racks 33 and move the davit cranes toward the outboard end of the trackways until their outboard movement is arrested by the trackway stops 45. The revolution of the cranes 41 in the opposite direction to that indicated by arrow, causes the davit cranes to move towards the inboard end of the trackways. When the davit cranes have attained their outboard position, the nut 25 is positioned on the bolt 24 to release the brake strap 22 from the friction drum 21, and permit the friction drum and the winding shaft 17 to freely revolve by the unwinding action of the davit falls as the boat descends by gravity. To raise the boat the pinion 19 is revolved by the crank 20. The revolution of the pinion 19 revolves the spur wheel 18 and winding shaft 17 to wind the davit falls on the winding drums 26. The winding of the davit falls on the winding drums 26 raises the boat to the top of the davit cranes and when the boat has been raised the nut 25 is turned on the bolt 24 to tighten the brake strap 22 against the friction drum and prevent the unwinding revolution of the friction drum and winding shaft when the power is removed from the crank 20. The crank 41 is then operated to move the davit cranes to their inboard position and bring the keel of the boat above the center of the boat saddles which have been previously raised to an upright position and locked by the saddle hooks 42. The nut 25 is then turned to slacken the brake strap 22 to permit of the unwinding revolution of the friction drum, heaving shaft, and winding drums, so that the boat can descend to the boat saddles. When the boat is seated on the boat saddles the lashing hooks 43 are engaged with the boat gunwales and the boat lashings 44 are tightened until the keel and bottom of the boat are securely held in contact with the boat saddles. When the boat lashings have been tightened the pinion 19 is turned to revolve the spur wheel 18 and winding shaft 17 to wind up the slack of the davit falls.

Having thus fully described my invention what I claim as new and desire to secure by Letters Patent is:—

1. A boat launching and stowing apparatus comprising two parallel trackways leading to the ship's side, a rack for each trackway, and a davit carriage consisting of a davit crane movable on each of said trackways, a transverse beam connecting the davit cranes together so that they will move unitedly, a transverse heaving shaft mounted in bearings connected to the davit carriage, pinions mounted on the transverse shaft engaging with said racks, and operable means for actuating the heaving shaft, said operable means consisting of a worm shaft journaled in bearings connected to the davit

carriage, a worm mounted upon the worm shaft, a worm wheel mounted upon the heaving shaft engaging with the worm, a spur wheel mounted on the worm shaft, a pinion shaft journaled in bearings connected to the davit carriage, a pinion mounted on the pinion shaft and means for causing the rotation of the pinion shaft.

2. A boat launching and stowing apparatus comprising two parallel trackways leading to the ship's side, a rack for each trackway, and a davit carriage consisting of a davit crane movable on each of said trackways, a transverse beam connecting the davit cranes together so that they will move unitedly, a transverse heaving shaft mounted in bearings connected to the davit carriage, pinions mounted on the transverse shaft engaging with said racks, and operable means for actuating the heaving shaft, said operable means consisting of a worm shaft journaled in bearings connected to the davit carriage, a worm mounted upon the worm shaft, a worm wheel mounted upon the heaving shaft engaging with the worm, a spur wheel mounted on the worm shaft, a pinion shaft journaled in bearings connected to the davit carriage, a pinion mounted on the pinion shaft and means for causing the rotation of the pinion shaft, and a winding shaft mounted in bearings connected to the davit carriage, idlers connected to the davit cranes, winding drums mounted upon the winding shaft and davit falls passing over the idlers to be wound on, and unwound from, the winding drums.

3. A boat launching and stowing apparatus comprising two parallel trackways leading to the ship's side, a rack for each trackway, and a davit carriage consisting of a davit crane movable on each of said trackways, a transverse beam connecting the davit cranes together so that they will move unitedly, a transverse heaving shaft mounted in bearings connected to the davit carriage, pinions mounted on the transverse shaft engaging with said racks, and operable means for actuating the heaving shaft, said operable means consisting of a worm shaft journaled in bearings connected to the davit carriage, a worm mounted upon the worm shaft, a worm wheel mounted upon the heaving shaft engaging with the worm, a spur wheel mounted on the worm shaft, a pinion shaft journaled in bearings connected to the davit carriage, a pinion mounted on the pinion shaft and means for causing the rotation of the pinion shaft.

davit carriage, a pinion mounted on the pinion shaft means for causing the rotation of the pinion shaft, a winding shaft mounted in bearings connected to the davit carriage, winding drums mounted upon the winding shaft, idlers connected to the davit cranes, davit falls passing over the idlers to be wound on, and unwound from, the winding drums, a spur wheel mounted on the winding shaft, a pinion shaft mounted in bearings connected to the davit carriage, a pinion mounted on the pinion shaft engaging with the spur wheel of the winding drum and means for causing the rotation of the pinion.

4. A boat launching and stowing apparatus comprising two parallel trackways leading to the ship's side, a rack for each trackway, and a davit carriage consisting of a davit crane movable on each of said trackways, a transverse beam connecting the davit cranes together so that they will move unitedly, a transverse heaving shaft mounted in bearings connected to the davit carriage, pinions mounted on the transverse shaft engaging with said racks, and operable means for actuating the heaving shaft, said operable means consisting of a worm shaft journaled in bearings connected to the davit carriage, a worm mounted upon the worm shaft, a worm wheel mounted upon the heaving shaft, a spur wheel mounted on the worm shaft, a pinion shaft mounted in bearings connected to the davit carriage, a pinion mounted on the pinion shaft and means for causing the rotation of the pinion shaft, and a winding shaft mounted in bearings connected to the davit carriage, winding drums mounted upon the winding shaft, idlers connected to the davit cranes, davit falls passing over the idlers to be wound on, and unwound from, the winding drums, a spur wheel mounted on the winding shaft, a pinion shaft mounted in bearings connected to the davit carriage, a pinion mounted on the pinion shaft engaging with the spur wheel of the winding drum, means for causing the rotation of the pinion, a friction drum mounted on the winding shaft and an adjustable friction strap engaging with the friction drum.
